CLAIM

The ornamental design for a hanger for scarf and leggings, as shown and described.

DESCRIPTION

FIG. 1 is a top, front, right side perspective view of a hanger for scarf and leggings showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of portion 8 in FIG. 1;

FIG. 9 is an enlarged view of portion 9 in FIG. 6; and,

FIG. 10 is an enlarged view of portion 10 in FIG. 7.

The dash-dot-dash broken lines define the boundary of enlarged views of the hanger for scarf and leggings and form no part of the claimed design.
